EXTENSION FOR FLY SWATTERS

Filed May 10, 1929

John P. Haberle

INVENTOR

BY Victor J. Evans

ATTORNEY

Robert F. Sibley
WITNESS:

UNITED STATES PATENT OFFICE

JOHN P. HABERLE, OF GLEN OLDEN, PENNSYLVANIA

EXTENSION FOR FLY SWATTERS

Application filed May 10, 1929. Serial No. 361,963.

The object of this invention is the provision of simple means designed to have removably attached to a swingable element thereon a fly swatter which, upon vertical movement 5 of the rod or handle member of the device will be forcibly swung, so that when the end of the device is arranged against a ceiling flies resting upon such ceiling will be killed in an easy and convenient manner.

10 To the attainment of the foregoing the improvement consists in the construction, combination and operative association of parts, one satisfactory embodiment of which is disclosed by the accompanying drawings.

15 In the drawings:

Figure 1 is a perspective view of the improvement.

Figure 2 is a transverse sectional view approximately on the line 2—2 of Figure 1.

20 Figure 3 is a sectional view approximately on the line 3—3 of Figure 2.

Figure 4 is a perspective view of the member which is attached to the rod.

25 Figure 5 is a similar view of the member which is slidably associated with the member illustrated by Figure 4.

Figure 6 is a perspective view of the rocker arm illustrating the manner in which the handle of a fly swatter is removably clamped 30 thereon.

In carrying out my invention I make use of a light rod 1 of a determined length. The rod is substantially rectangular in cross section and adjacent to its outer end has fixed 35 thereon a cross sectional V-shaped metal plate member 2. The plate member 2 projects a suitable distance beyond the end of the rod, and the said plate member 2 has its edges formed with outwardly directed flanges 3.

40 The flanges 3 of the member 2 that are fixed on the rod 1 are received in guides 4 formed on the flanged and bent edges of a second V-shaped member 5. The member 5 has its outer end formed with a flat head 6.

45 Both the members 2 and 5 are provided with openings 7 and 8, respectively, and through these openings there is passed one end of a rocker arm 9. The rocker arm is formed with an inner lug 10 and with an 50 outer lug 11. These lugs may be removably

secured on the rocker arm 9 and are designed to prevent the rocker arm from passing longitudinally through the openings 7 and 8.

On its outer end the rocker arm 9 has fixed thereto a metal socket 12 designed to receive 55 therein the handle 13 of a fly swatter 14. A binding element 15 holds the handle 13 in the socket, and the combined weight of the arm and the fly swatter will cant the rocker arm downwardly and thereby project the 60 headed member 5 a considerable distance outwardly from the member 2. Thus when the head 6 is arranged against the ceiling in a room and the fly swatter is positioned below a fly to be killed, an upward push on the rod 65 1 will swing the rocker arm in an upward direction, causing the swatter 14 to be brought violently against the insect and destroy the same.

70 With a simple construction as above described it will be noted that the flies or other insects lighting upon the ceiling of the room may be exterminated in an easy and convenient manner and further that the simplicity of my construction and the advantages thereof will be understood and appreciated.

75 Having described the invention, I claim:

1. A rod having an extension, a headed member guided on said extension, both the extension and the body of the head member 80 being provided with openings, a rocker arm received through the openings and designed to have the handle of a fly swatter removably attached thereto and whereby the combined weight of the rocker arm and the fly swatter 85 will normally swing the rocker arm downwardly and project the headed member a distance outwardly from the rod, for the purpose set forth.

2. A device for the purpose set forth, a rod, a substantially V-shaped member fixed to the rod and extending beyond one end thereof, a second substantially V-shaped member having a headed end, guide means integrally formed between both of the V-shaped members and both of said V-shaped members having an opening therethrough, a rocker arm received through the openings, means on the rocker arm for holding the same from passage through the openings, a socket 95 100

- on the outer end of the rocker arm to receive the handle of a fly swatter therein, means for binding the handle in the socket, the combined weight of the fly swatter and rocker arm designed to swing the rocker arm downwardly with respect to the rod when the latter is in vertical position and to move the slidable V-shaped member outwardly therefrom.
- 10 3. In a device for the purpose set forth, a rod, an angle plate member secured to the rod and extending beyond one end thereof, a member guided for slidable movement on the plate member, a rocker arm passing through the plate member and through the slidable member, lugs on the rocker arm to contact with the outer faces of the plate and slidable member and said rocker arm carrying a fly swatter whose weight cant the said rocker arm to cause the slidable member to move a predetermined distance outward on the plate, for the purpose set forth.
- 15 20

In testimony whereof I affix my signature.
JOHN P. HABERLE.
